(57) **CLAIM**

The ornamental design for an earpiece device, as shown and described.

DESCRIPTION

FIG. 1 is a perspective view illustrating a design for an earpiece device shown in an extended configuration according to one embodiment;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is a view illustrating an environment of the earpiece device of FIGS. 1-7 coupled to an electronic computing device;

FIG. 9 is a perspective view illustrating a design for the earpiece device shown in a bent configuration;

FIG. 10 is a front view thereof;

FIG. 11 is a back view thereof;

FIG. 12 is a side view thereof;

FIG. 13 is another side view thereof;

FIG. 14 is a top view thereof;

FIG. 15 is a bottom view thereof;

FIG. 16 is a view illustrating an environment of the earpiece device of FIGS. 9-16 positioned within an ear of a user; and, FIG. 17 is a side view of the earpiece device in another bent configuration.

The broken lines and the unshaded regions bounded by broken lines of the preceding FIGURES illustrate boundaries for the FIGURES; however, the broken lines and the unshaded regions bounded by broken lines form no part of the claimed design. Non-oblique line shading is meant to show contour and not surface ornamentation.
